MATERIAL CUTTING AND MEASURING
DEVICEJoseph F. Jeckert and Benjamin W. Kleinfeld,
Clifton, N. J.

Application April 9, 1946; Serial No. 660,826

4 Claims. (Cl. 242—55.5)

1

This invention relates to display and dispensing devices for roll goods, such as linoleum. Previous devices of this character have had the disadvantage of occupying too much space and being too complicated in their construction, and operation.

This invention will be easily movable and positioned whereby one dispensing unit may be used for a plurality of display devices.

Furthermore, this dispensing unit may be easily attached or detached to any of the display devices, and removed when not in use, thereby reducing the store space for the display device to a minimum.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a top plan view of our invention, embodying the display and dispensing device.

Figure 2 is a front elevational view of same, partly in section.

Figure 3 is a top plan view, showing the arrangement of a plurality of display devices.

Figure 4 is a front elevational view thereof.

Figure 5 is an enlarged transverse vertical sectional view taken on line 6—6 of Figure 3.

Figure 6 is a transverse horizontal sectional view taken on line 6—6 of Figure 5.

Figure 7 is an enlarged transverse vertical sectional view of a part of our dispensing device.

Figure 8 is a horizontal sectional view taken on line 8—8 of Figure 7.

Figure 9 is a similar view, showing some parts in a different position.

Figure 10 is a top plan view of another part of our dispensing unit.

Figure 11 is a front elevational view thereof.

Figure 12 is a side elevational view of Figure 11.

Figure 13 is a fragmentary view, showing parts of Figure 12 in a different position.

Figures 14, 15 and 16 are detail views of parts of our dispensing device.

Referring now to the drawings and particularly to Figures 1 and 2, our invention consists of a display unit 20, a dispensing unit 21 and a measuring and cutting unit 22. This display unit or units 20 may be secured to the floor or a platform 23 as by means of bolts 24, passing through openings in the base 25. The latter is provided with a centrally located opening 26 to receive the

2

lower end 27 of a shaft 28, resting on a flange 29 fast in the shaft 28.

Sleeves 30 and 31 are slidably arranged on the shaft 28 between the flange 29 and a cap 32 on the shaft 28. Springs 33 may be secured to the sleeves 30 and 31 as shown at 34 to engage the cores 35 of rolls 36. A disk 37 is rotatably arranged on a hub 38 within a recess 39 of the base 25.

10 Thus to insert a supply roll of goods, it is only necessary to place the core 35 of one end of the roll 36 over the springs 33 and bringing the end of the roll to rest upon the disk 37.

It is thereby easily understood that the roll is 15 rotatably mounted on the display device 20, since it bears upon the disk 37, which is revolvable on the hub 38, and thus goods may be easily unrolled.

A hollow post 40 is secured to the base 25 as 20 shown at 41 and adapted to receive a shaft 42, which latter extends into a rectangular arm 43 provided with a lining 44. A helical spring 45 is secured on one end to the shaft 42, as shown at 46; while the other end is attached to a collar 47, having a set screw 48.

25 Thus when a roll of goods has been placed upon the stand 25, the arm 43 with its lining 44 is brought into frictional contact with the roll 36. This friction is easily adjustable by means of the spring 45, collar 47 and set screw 48, as may readily be understood from Figure 5. By means of this arrangement an opening up of the roll after the removal of any tieing means, is thereby prevented. Extensions 49 are formed on the front edge 50 of the bases 25 and are provided with depressions or notches 51.

As herebefore mentioned, a plurality of my display devices may be easily positioned without occupying too much space.

In Figures 3 and 4 we have shown such an arrangement in which display devices 20, 20a, 20b, 20c, 20d, and 20e are placed adjacent to one another and secured to the floor or platform 23 by means of bolts 24. Rolls 36, 36a, 36b, 36c, 36d and 36e; resting on disks 31, 31a, 31b, 31c, 31d and 31e and engaged by friction arms 43, 43a, 43b, 43c, 43d and 43e are shown therein. Although we have shown our display devices arranged in a continuous row, this arrangement may be changed if so desired or necessary.

50 Referring now to the dispensing device 21 as shown in Figures 1, 2 and 7, it consists of a platform 52 supported on rollers 53 and having an upwardly extending frame 54. A post 55 having a flange 56 is secured to the platform 52 and provided with a groove 57. A tubular member 58 ex-

tends into enlarged portions 59 and 60 at its ends and has attached to one end a gear 61 covered by a plate 62. The member 58 with the bore 63 is rotatably arranged on the post 55 and held in place by means of a screw 64 engaging the groove 57.

A substantially circular housing 65 is secured to the enlarged upper end 60 as by screws 66 and by the screws 64 to the enlarged lower portion 59 and has attached close to one edge thereof a vertically extending angular member 67. To the other edge is hinged as at 68 a radial member 69.

A cam member 70 is pivoted at 71 in the enlarged lower end 59 and at 72 in the enlarged upper end 60, and has a lever 73 attached thereto. By means of the lever 73, the cam member 70 may be brought into engagement with the radial member 69.

A vertically extending cam 74 is pivoted to the lower end 59 as shown at 75 and to the upper end 60 as at 76 and has secured thereto a lever 77, by means of which the cam 74 may be brought into engagement with the open end of the housing 65.

A shaft 78 is journaled at its lower end in the platform 52 and carries a gear 79 to mesh with the gear 61 of the tubular member 58. At its upper end the shaft 78 passes through an arm 80 formed in the frame 54 and carries a bevel gear 81, to mesh with a bevel gear 82 connected on a shaft 83 and rotatably arranged in the bearing 84 formed on the frame 54. A set screw 85 is provided in the bearing 84 to lock the gears in any desired position, as may be seen from Figure 7.

A crank handle 86 is secured to the shaft 83, by means of which the bevel gears 81 and 82 and the gears 79 and 61 may be turned, thus rotating the tubular member 58 with all its connecting parts.

A U-shaped handle 87 is connected to the frame 54 as at 88 to allow for easy manipulation to and from any of the display units 20 to which the dispensing unit 21 is to be connected, the operation of which will be described later.

The gear 61 is covered by a guard 89, while the rest of the mechanism is enclosed by the back 90 attached to the frame 54 and by the housing 91, which at the top 92 has a block 93 attached thereto, to provide a bearing for the slideable rod 94. To the latter is connected an arc-shaped member 95 provided with a lining 96. The rod 94 may be locked in any position by means of a set screw 97 as shown in Figures 1, 2 and 7.

Pawl 98 are secured to the platform 52 at 99 and normally held in a downward position by springs 100. (See Figures 1 and 2.) The pawls 98 terminate into hook portions 101 to engage the notches 51 in the extensions 49 of the base 25 and are held in such an engagement by the springs 100. These pawls 98 may be released from the notches 51 by means of cam portions 102 provided on a shaft 103, which latter is journaled to the platform 52 as at 104 and terminates into a handle 105.

The pawls 98 come into locking position with the notches 51 when the forward edge 106 of the platform 52 comes into engagement with the edges 107 of the extensions 49, thus forming a rectangular space 108 to accommodate the base of the cutting mechanism hereinafter to be described.

Referring now to the cutting mechanism

22 and particularly to Figures 1, 2, 10, 11 and 12, a square post 109 is provided with a base 110 with approximately the width of the rectangular area 108 to allow a sliding movement of the post 109.

At the top the post 109 has secured thereto a bar 109a, to slidably accommodate a U-shaped cross member 111, having downward extensions 112 and 113 and extending into arms 114 and 115. The arm 114 is provided with a downwardly extending shaft 116, accommodating sleeves 117 and 118 to which are secured springs 119, the latter to engage the core 35 of the roll 36, when inserted into the top of the roll.

15 The arm 115 extends into a yoke 120 to engage a roller 121 loosely mounted on the extension 122 of the tubular member 58, the roller 121 being held in place by a bolt 123 and a washer 124. The roller 121 may be locked into the yoke 120 by a latch 125 secured to the arm 115 as at 126.

Thus it will now clearly be understood from the foregoing description that by the insertion of the springs 119 into the core 35 of roll 36 and the engagement of the base 110 within the space 108, the cutting unit 22 is thus brought in proper relation with the roll 36 and held in this relation by the latch member 125.

A bar 127 is slidably arranged in relation to the post 109 by means of rods 128 and secured by nuts 129 thus forming an opening 130 through which the end 131 of the roll 36 may be passed. Between the post 109 and the bar 127 are interposed springs 132 to normally keep the opening 130 in an open position. The other ends of rods 128 are pivoted at 133 to cam members 134, formed with projections, said cam members are connected to rods 135 provided with reduced portions 136 slideable in rods 128 and surrounded by tension springs 137, one end of which is connected to the rods 135. The other ends of springs 137 are secured at 139 to the rods 128, which in turn are pivoted at 140 to a ratchet 141 on a stud 142 rotatably mounted in a bracket 143 fast on the post 109. The stud 142 also carries an arm 144 by means of which the ratchet may be rotated and held in position by a pawl member 145 pivoted at 146 to the post 109.

Secured at its upper and lower end of post 109 as shown at 147 and 148, is a bar 149 to accommodate a slide 150, provided with rollers 151 to engage the bar 149. The slide 150 is provided with a handle 152. A circular cutting knife 153 is rotatably secured to the slide 150 at 154 and held in a fixed position by a screw 155 in the slide 150, entering into one of the holes 156 of the knife 153. Thus only part of the cutting edge 157 is in use at any time, as clearly shown in Figure 12, and if this part of the knife 153 through extensive use becomes worn, an unused section of the knife may be exposed by means of the screw 155 and holes 156. By this arrangement the knife may be used for a considerable length of time, before a removal for resharpening or replacement becomes necessary.

65 The post 109 is provided with extensions 158 having bayonet slots 159 to accommodate a bracket 160 of a metering device 161. The mechanism of this device is not shown, but connected with it is a downwardly extending shaft 162 journaled in the bracket 160. A gear 163 is secured to the shaft 162 and adapted to mesh with a gear 164 fast on a shaft 165. The lower end of this shaft 165 carries a friction roller 166, while a similar roller 167 may extend from the shaft 162. 70 The shaft 165 is journaled in a sleeve 168 pivoted

at 168 within the bracket 160. A spring 170 is attached to a groove 171 formed in the shaft 165 while the other end of said spring is secured to the bracket 160 as at 172, thus tending to force the friction roller 166 toward the roller 167.

In the drawings has been shown a roll of a width of 6 feet, and when to be dispensed and measured, the metering device 161 is mounted in the slot 159 nearest the top of the post 109 as shown in Figures 2 and 11, and when a roll of lesser width is to be used, extensions 158 may be provided at intervals to conform with the width of the rolls, only one of these extensions being shown in the drawings.

The slide 150 is frictionally held in its upper position by a ball 173 engaging a depression 174, the ball being kept in engagement with the depression 174 by a spring 175 in an opening 176 of the post 109; this opening being closed by a screw 177. The cross member 111 is prevented from sliding off the bar 109a by means of a screw 178.

Describing now more fully the operation of the invention, the springs 119 of the cutting unit 22 are inserted into the core of the roll from which the material is to be dispensed, the base 110 to be placed between the extensions 49 and held within this space by the forward edge 106 of the platform 52, which is locked in position with the display unit 20 by means of pawls 101, the latch 125 also having been locked to the roller 121 of the dispensing unit 21. The end 131 of a roll 36, on the display unit 20 is fed between the friction rollers 166 and 167 and through the opening 130 into the dispensing unit 21 and within the circular housing 65 until the edge of the end 131 comes into engagement with the angular member 67. The cam member 74 is then by means of the lever 77 brought into engagement with the end 131, thus forcing the latter and holding it firmly against the open end of the housing 65.

The member 69 is then brought in its expanded position by means of the cam 70 and lever 73, as shown in dotted lines in Figure 8 and in full lines in Figure 9.

When the desired amount or length as indicated by the measuring device has been wound on the roll 65, the gear mechanism and the yoke 95 with the lining 96 is then brought into engagement with the wound material and locked by the screw 97 to prevent unwinding of the material; 61, 79, 81 and 82 may then be locked by the screw 85. The bar 127 is then brought in close contact with the material 131 by means of the rods 128, cams 134, rods 135 and 138, and the ratchet 141 and pawl 145, thus holding the material clamped firmly within the slot 130. The slide 150 with the knife 153 may then be moved downward on the guide bar 149 by means of the handle 152 and the knife 153 engaging the edge 180 of the post 109 will then cut and separate the dispensed material from the material still left on the roll. The gears may then be unlocked and the remaining end wound on the housing 65 at which stage the wound material is then ready for tying by strings or any other suitable means.

To facilitate easy removal of the tied up roll, the member 69 is brought back into its innermost position after the cam 74 has been released from engagement with the material 131. The dispensing device 21 may then be disengaged from the display unit 22 and moved to any suitable place for the removal of the roll.

To further facilitate the removal of the dispensed roll, the platform may be tilted and rested

on the rollers 53 and the handle 87 as shown by the dotted lines of Figure 7.

It is obvious that changes may be made in the form, construction and arrangement of the several parts, as shown, within the scope of the appended claims, without departing from the spirit of the invention, and we do not, therefore, wish to limit ourselves to the exact construction shown and described herein.

10 What we claim as new, and desire to secure by Letters Patent of the United States, is:

1. The combination of a dispensing unit, and a measuring unit with a display unit, the latter having a base, a rotatable disk mounted thereon, a shaft turnable in said base, sleeves slidably disposed on said shaft, and expandible springs arranged between the ends of said sleeves, whereby to engage a roll of material, a hollow member secured to the base, a vertical shaft rotatably arranged in said hollow member, said shaft having a rectangular curved arm at one end thereof provided with friction means to engage said roll of material, an adjustable collar movable on said hollow member, and a spring arranged between said collar and rectangular arm, extensions formed on the base and having depressions therein, means arranged upon the dispensing unit and adapted to engage said depressions, and the measuring unit interposed between the extensions of the base of the display unit and the dispensing unit.

2. The combination of a dispensing unit, and a measuring unit with a display unit, the latter having a base, a rotatable disk mounted thereon, a shaft turnable in said base, sleeves slidably disposed on said shaft and expandible springs arranged between the ends of said sleeves, whereby to engage a roll of material, a hollow member secured to the base, a vertical shaft rotatably arranged in said hollow member, said shaft having a rectangular curved arm at one end thereof provided with friction means to engage said roll of material, an adjustable collar movable on said hollow member, and a spring arranged between said collar and rectangular arm extensions the latter being formed upon said base and having depressions therein, the dispensing unit having a base, pawls arranged upon the latter and adapted to engage the depressions in the extensions of the base in the display unit, springs mounted on the base of the dispensing unit and adapted to actuate said pawls, a shaft rotatably arranged on the latter base and having an operating arm at one end thereof, cam members disposed on said pawls whereby to disengage the latter from the depressions in the base of the display unit, a vertical shaft extending from the base of the dispensing unit, a hollow member surrounding the shaft, an enlarged portion formed at the bottom and top of said hollow member, and a substantially circular housing secured to said enlargements.

3. In an invention, as claimed in claim 2, and wherein said circular housing has an angular member arranged within said housing and adapted to engage the end of a roll of material, a cam member journaled in the upper and lower enlargements of the hollow member and formed with an operating lever whereby to engage and secure the end of the material within the circular housing, an arc-shaped member hinged to the circular housing, a second cam member journaled in said upper and lower enlargements and provided with an operating lever adapted to engage said arc-shaped member whereby to in-

crease the periphery during the winding operation of the material and decrease the periphery during removal of the dispensed material.

4. In an invention as claimed in claim 2, and wherein said circular housing comprises an angular member arranged within said housing and adapted to engage the end of the roll of material, a cam member journaled in the upper and lower enlargements of the hollow member and formed with an operating lever whereby to engage and secure the end of the material within the circular housing, an arc-shaped member hinged to the circular housing, a second cam member journaled in said upper and lower enlargements and provided with an operating lever adapted to engage the arc-shaped member, a gear attached to the lower enlargement of the hollow member, and meshing with a second gear, the latter gear being mounted on a shaft journaled in the base, a bevelled gear secured to the upper end of said shaft and adapted to mesh with a second bevelled gear mounted upon a horizontally disposed shaft the latter being journaled in a vertically extending frame member of said base, a crank-handle attached to said horizontal shaft, whereby in combination with said gears to operate the dispensing of the material, a housing enclosing said gears, a member

secured to the top of said housing and a rod slidably arranged in said member, a screw for adjusting said rod, an arc-shaped member mounted at the end of said rod and provided with friction means to engage the dispensed material.

5 JOSEPH F. JECKER.
